UNITED STATES PATENT OFFICE.

CHRISTIAN DANCEL, OF NEW YORK, N. Y.

MACHINE FOR SPLITTING LEATHER.

SPECIFICATION forming part of Letters Patent No. 244,196, dated July 12, 1881.

Application filed May 4, 1881. (No model.)

To all whom it may concern:

Be it known that I, CHRISTIAN DANCEL, a citizen of the United States, residing at New York, in the county and State of New York, 5 have invented new and useful Improvements in Machines for Splitting Leather and other Materials, of which the following is a specification.

This invention consists in the combination 10 of a splitting-knife, a gage, and a feed-dog (one or more) the working-surface of which extends beyond the cutting-edge of the knife and forms a support for the material after the same has been split; also, in the combination 15 of a splitting-knife, a gage, a carriage containing two or more feed-dogs, and springs, one for each feed-dog, to enable said feed-dogs to adapt themselves to the irregularities of the material to be split; further, in certain mechanism for allowing the feed-dog or feed-dogs 20 to drop as the same recede, as will be herein-after more fully described.

This invention is illustrated in the accompanying drawings, in which Figure 1 represents 25 a longitudinal vertical section in the plane x x , Fig. 2. Fig. 2 is a transverse vertical section in the plane y y , Fig. 1. Fig. 3 is an inverted plan, partly in section.

Similar letters indicate corresponding parts. 30 In the drawings, the letter A designates a platform which rests upon suitable supports, B, and which is provided with guideways a a , in which moves the carriage C. Near one end of this platform is secured the splitting-knife 35 D by two or more set-screws b, which pass through slots in the knife, so that the cutting-edge of the knife can be adjusted in the proper relation to the gage E. In the example shown in the drawings this gage consists of an L-shaped piece of cast-iron, which is secured by 40 set-screws c c to a yoke, F, that rises from and is firmly secured to the platform A. The set-screws c c pass through slots d d, Fig. 2, and a screw, e, serves to raise or lower the gage, so 45 as to accommodate the same to the thickness of the material to be split. Instead of using a flat L-shaped gage, however, I can use a roller-gage or a gage of any suitable form or shape.

50 The splitting-knife D which I have shown in the drawings is stationary, but said knife

may be connected to a suitable mechanism for imparting to the same a reciprocating motion during the operation of cutting, or a band-knife may be substituted for the stationary 55 knife.

In the front end of the carriage C is formed a recess for the reception of the feed-dogs G, and a bar, H, which is screwed to the carriage, retains said feed-dogs in the recess. The working-surfaces of the feed-dogs extend beyond the cutting-edge of the knife, and each of the feed-dogs is exposed to the action of a separate spring, f, so that the same accommodate themselves to the inequalities of the material to be split. This arrangement is essential 60 if my machine is used for splitting hides or leather which are not of uniform thickness throughout; but if my machine is used for splitting pasteboard or other materials of uniform thickness, a single feed-dog may be used. 65

The springs f rest upon a platform, g, which extends from a lever, I, mounted on a shaft, J, that has its bearings in a hanger, K, extending from the carriage C. From said lever 70 extend arms L, which form the bearings for a rod, h, that forms the fulcrum for a series of bell-crank levers, i j, one for each feed-dog. The long arms i of these bell-crank levers extend over the spring f, and they are pressed 75 up against friction-rollers k, secured in the shanks of the feed-dogs, while the short arms j of said bell-crank levers are opposite to stops l, secured in the platform g in such a position that the feed-dogs cannot be forced up far 80 enough to come in contact with and injure the cutting-edge of the knife.

The material to be split is placed upon the carriage C beneath the gage E, its forward end being supported by the feed-dogs G, which 85 are provided with serrated or toothed faces, and as the carriage begins to move forward the serrated faces of the feed-dogs G are pressed up against the under surface of the material, and are advanced by the forward 90 movement of the table, thereby causing said dogs to force the material forward against the cutting-edge of the knife. During the operation of splitting that portion of the material beneath the knife is still supported by the 95 feed-dogs, which carry the same forward and prevent it from becoming jammed, so that the 100

splitting operation can be carried on without difficulty. When the carriage recedes the feed-dogs are allowed to drop, so as to clear the material to be split.

5 The mechanism for moving the carriage consists of a crank, *M*, which is firmly secured on the outer end of a revolving shaft, *m*, mounted in a box, *n*, which is secured to the platform *A*. On the inner end of this shaft is mounted 10 a cam-disk, *n'*, which carries an eccentric-pin, *o*, that connects by a strap, *p*, with a pin or rod, *q*, secured in the carriage *C*. The shaft is turned in the direction of the arrow, (marked near the crank in Fig. 1,) and as it moves toward the position shown in Fig. 1 the cam-disk acts upon the lever *I* and the feed-dogs are forced up, while at the same time the carriage is drawn forward, which forward movement effects the advance motion of the feed-dogs. As the motion of the shaft proceeds 20 the cam-disk *n* releases the lever *I*, so that the bell-crank levers *i j*, springs *f*, and platform *g* sink down, the springs *f* are prevented by the stops *l* from acting on the feed-dogs, and 25 the feed-dogs drop clear of the material while the carriage is moved back, and when the carriage has reached the back end of its stroke the cam-disk acts again on the lever *I*, so that when the forward motion of the carriage commences the material to be split is carried forward by the feed-dogs.

It is obvious that a pulley may be substituted for the crank if it is desired to drive my machine by mechanical power.

What I claim as new, and desire to secure 35 by Letters Patent, is—

1. The combination, substantially as herein-before described, of the splitting-knife, the gage, and a feed-dog mechanism the working- 40 surface of which forms a support for the ma- terial after the same has been split.

2. The combination, substantially as herein-before described, of the splitting-knife, the gage, and a series of feed-dogs each of which is constructed to adapt itself to the surface of 45 the material to be split independent of the remaining feed-dogs.

3. The combination, substantially as herein-before described, of the splitting-knife, the gage, the carriage containing two or more feed- 50 dogs, and the springs, one for each feed-dog.

4. The combination, substantially as herein-before described, of the splitting-knife, the gage, the carriage containing a series of feed- 55 dogs, the spring or springs acting on the feed dog or dogs, the platform supporting said spring or springs, the bell-crank levers *i j*, the stops *l*, the lever *J*, and the cam-disk *n'*.

In testimony whereof I have hereunto set my hand and seal in the presence of two sub- 60 scribing witnesses.

CHRISTIAN DANCEL. [L. S.]
